UNITED STATES PATENT OFFICE

PIETRO ROCA, OF FLUSHING, NEW YORK

SANITARY ATTACHMENT FOR TELEPHONE MOUTHPIECES

Application filed May 14, 1929. Serial No. 362,995.

This invention relates to improvements in sanitary attachments for telephone mouthpieces and its primary object is to provide a simple and relatively inexpensive device provided with means which make it possible to attach the device to mouthpieces of various diameters such as are used in telephones of the ordinary type, telephones of the bracket type and all kinds of speaking tubes for house telephones and the like.

Another object of this invention is to provide a relatively inexpensive device adapted to be made from a single blank having means for quickly attaching it to a telephone mouthpiece and means for retaining a capsule of a disinfectant material, whereby the dangers of germs due to the promiscuous use of telephones and like apparatus are eliminated.

A further object is to provide a device of the character specified adapted to be held within the mouthpiece of a telephone or like instrument, without interfering with the operation thereof.

Other objects and advantages of the present invention will more fully appear as the description proceeds and will be set forth and claimed in the appended claims.

My invention is illustrated in the accompanying drawings in which:

Fig. 1 is a side sectional view of a telephone mouthpiece equipped with my device;

Fig. 2 is a front elevation thereof;

Fig. 3 is a view in perspective of a blank from which my improved device may be formed; and

Fig. 4 is a view in perspective of a disinfectant capsule or cartridge adapted to be used in connection therewith.

It is well known that telephone mouthpieces are potential carriers of disease and infection, especially in the case of public booths where a great number of people use the same telephone at frequent intervals.

It is therefore desirable to provide some sort of protection against the dangers arising from this condition. A device used for this purpose should be inexpensive and should be adapted to be easily placed in position or removed therefrom; above all, the device should be designed so as not to interfere

with the proper reception of the sound vibrations by the telephone instrument.

I am aware that various devices have been developed with the aim of protecting the telephone user against infection, but I have always found that the usefulness of these devices was seriously curtailed due to their construction causing interference with the proper transmission of sound.

The present invention answers all practical requirements from a sanitary and economical standpoint and at the same time does not in the least interfere with the operation of the telephone instrument.

Referring to the drawings, 10 designates an ordinary telephone mouthpiece having a perforated bottom part 11. My improved device consists of a holder 12 formed integral with a plurality of radially extending arms 13, the ends of which are adapted to be folded over the edge of the telephone mouthpiece as shown at 14.

The holder is formed by bending rearwardly and then inwardly other radial extensions such as 15 interposed between the arms 13. The resulting structure is an open work receptacle comprising a plurality of circumferentially arranged members adapted to grip a capsule or cartridge 16 which is made of disinfecting material of a suitable consistency. For instance, the capsule may consist of camphor or naphthalene mixed with creosote or other such substance or mixture of substances.

The device may be made in the form of a blank 17 such as illustrated in Fig. 3, said blank comprising a plurality of relatively long radially extending arms 13 and a plurality of relatively short arms or prongs 15, 16 radially extending therebetween.

The blank is made out of relatively light gauge metal, soft and easily bendable so that the long arms can be bent forwardly at their point of attachment to the central body portion of the device as shown at 18, and their outer ends may be bent to form a loop 14 embracing the edge of the mouthpiece. In this manner the arms may be made to project within the mouthpiece maintaining the

holder 12 centrally thereof, at a certain distance from the bottom part 11.

It is obvious that the arms can be bent at 18 at any desired angle so that the holder may be maintained in the proper position with respect to the bottom 11 of the mouthpiece. Furthermore, it will be seen that the outer ends of arms 13 can be bent over at the proper distance from the center so as to suit the diameter of the mouthpiece to which the device is applied.

Arms or prongs 15 may be bent rearwardly with equal ease and after the insertion of the capsule or cartridge 16 their tip ends may be bent inwardly as shown at 19, so as to retain the cartridge or capsule in position.

When a new capsule is to be inserted in place of an old one, arms or prongs 15 can be forced outwardly enough to clear the capsule and after the capsule has been replaced they can be once more forced back into position.

The diameter of the capsule is relatively small and receptacle 12 is of the same size, its diameter being much smaller than the diameter of the bottom part 11 of the mouthpiece. The sound waves can therefore reach the diaphragm through perforations 20, provided in bottom 11 practically unhampered by the device, said sound waves being freely admitted through the annular passage 21 between the capsule and the inner wall of the mouthpiece.

This is very important because any device which unduly obstructs the passage of the diaphragm is bound to seriously interfere with the normal operation of the telephone.

The device can be removed or replaced with the utmost ease, these operations requiring but a few seconds of the user's time.

Being made out of a single blank, the device can be produced at an extremely low price, although it is obvious that if desired, a blank provided with arms 13 may be made separately and are riveted or otherwise attached to the bottom of the receptacle.

Other minor changes may be made in the construction of the device without departing from the inventive idea. Therefore, I reserve the right to carry my invention into practice in all those ways and manners which may enter, fairly, into the scope of the appended claims.

I claim:

- 55 1. A device of the class described, consisting of a spider shaped metal blank having a plurality of radially extending arms, some of said arms being bent inwardly to form an open work receptacle adapted to retain a capsule of disinfectant material, and the other arms being bent outwardly to form hook shaped members adapted to retain the device on, and to position the same in relation to the mouthpiece to which the device is applied.
- 60 2. A device of the class described, adapted

for insertion in the mouthpiece of a sound transmitting instrument, comprising an open work receptacle adapted to retain a disinfectant capsule, and a plurality of soft metal arms radially extending from said receptacle, said arms being bendable by hand to suit the depth and diameter of the mouthpiece to which the device is applied.

3. A device of the class described, adapted for insertion in the mouthpiece of a sound transmitting instrument, comprising an open work receptacle adapted to retain a disinfectant capsule, and a plurality of soft metal arms radially extending from said receptacle, said arms being bendable by hand to suit the depth and diameter of the mouthpiece to which the device is applied, said receptacle having a diameter materially smaller than the diameter of the bottom part of said mouthpiece.

4. A device of the class described, consisting of a soft metal blank comprising a central disc portion, a plurality of relatively long arms radially extending therefrom, and a plurality of relatively short arms interposed therebetween, also radially extending therefrom, said short arms being bendable inwardly by hand, to retain a capsule of disinfectant material, and said long arms being also bendable by hand to suit the depth and diameter of the mouthpiece to which the device is applied.

5. A device of the class described, consisting of a soft metal blank comprising a central disc portion, a plurality of relatively long arms radially extending therefrom, and a plurality of relatively short arms interposed therebetween, also radially extending therefrom, said short arms being bendable inwardly by hand to form an open work receptacle adapted to retain a capsule of disinfectant material, said receptacle having a diameter materially smaller than the diameter of the bottom part of the mouthpiece to which the device is applied, and said long arms being bendable by hand to suit the depth and diameter of said mouthpiece.

6. A device of the class described, consisting of a soft metal spider shaped blank having a plurality of radially extending arms, some of said arms being bendable inwardly by hand to form an open work receptacle adapted to retain a capsule of disinfectant material, and the other arms being also bendable outwardly by hand, to form hook-shaped members adapted to retain the device on and to position the same in relation to the mouthpiece to which the device is applied.

PIETRO ROCA.
